Attorney.

UNITED STATES PATENT OFFICE.

HEZEKIAH POWELL, OF KANSAS CITY, MISSOURI.

ELECTRIC SHOE CLEANING AND POLISHING MACHINE.

Application filed March 31, 1924. Serial No. 703,270.

To all whom it may concern:

Be it known that I, HEZEKIAH POWELL, a citizen of the United States, residing at Kansas City, in the county of Jackson and State of Missouri, have invented certain new and useful Improvements in Electric Shoe Cleaning and Polishing Machines, of which the following is a specification.

My invention relates to electric shoe cleaning and polishing machines and one object is to provide a relatively simple, inexpensive and efficient machine of this character whereby shoes and boots may be cleaned and polished at a much less expenditure of time and labor than when such work is performed entirely by hand.

A further object is to arrange the parts in such manner that different kinds of brushes or other cleaning and polishing devices may be readily interchanged to suit the character of the work to be performed, whether the same be cleaning or polishing.

Another object is to provide means for conserving electric current by automatically closing a circuit leading to the motor of the cleaning and polishing machine when the same is applied to a boot or shoe, and means for automatically interrupting said current the instant the cleaning or polishing element is lifted from the boot or shoe.

Other objects will hereinafter appear and in order that the invention may be fully understood, reference will now be had to the accompanying drawing, in which:

Fig. 1 is an elevation, partly in section, of the cleaning and polishing machine.

Fig. 2 is an enlarged cross section on line II—II of Fig. 1.

In carrying out the invention, I employ a motor 2, the housing 4 of which is preferably of such length and diameter as to form a convenient handle for the operator.

6 designates a primary tubular shaft extending axially through the housing 4 and carrying the armature 8 of the motor 2.

10 designates a secondary shaft extending axially through the primary shaft 6 and having a pin-and-slot connection 12 therewith, so that it may move longitudinally within said primary shaft 6 and at the same time be driven thereby.

14 designates a self-opening switch which is arranged in a tubular extension 16 at one end of the motor housing 4. Said switch 14 comprises a pair of insulated movable con-

tact members 18, and a pair of insulated stationary contacts 20. The movable contacts 18 carry the motor terminals 22 and are normally held out of engagement with the contacts 20 by an intervening spring 24, which also, through the intermediacy of the insulation 26 between the contact members 18, pushes the secondary shaft 10 to the right, Fig. 1, until stopped by its shoulder 28 contacting the adjacent end of the primary shaft 6.

A cap 29 is screwed upon the end of the extension 16 to exclude dust from the switch 24.

An extension cord 30 provided with a plug 32 and connected to the contact members 20 is provided to enable the motor 2 to be readily connected to an ordinary lamp socket or other source, or supply, of electrical energy.

34 designates a cleaning or polishing element mounted upon that end of the secondary shaft 10 remote from the switch 14. Said cleaning or polishing element 34 has a slotted socket 36 for engagement over a stud 38 fixed to the secondary shaft 10. The foregoing arrangement permits different kinds of cleaning or polishing elements to be readily connected to the secondary shaft 10.

The operation briefly stated is as follows: 85 When the cleaning or polishing element 34 is pressed against a shoe or boot by pushing forwardly upon the motor 2, such pressure overcomes the resistance of the spring 24 and forces the contact members 18 and 20 90 into engagement with each other, thereby closing the motor circuit, whereupon the motor drives the cleaning and polishing element 34 through the intermediacy of the shafts 6 and 10. The motor circuit remains 95 closed so long as the cleaning and polishing element 34 is pressed against the shoe or boot which it is cleaning or polishing, but the instant it is removed from said shoe or boot the motor circuit is interrupted by the 100 spring 24 opening the switch 14.

From the foregoing description it will be understood that I have provided a combination of coacting elements whereby the current is automatically cut off from the motor, except at such times when the cleaning and polishing element 24 is in actual operation, and while I have shown and described the preferred form of the invention, I reserve the right to make such changes in the 110

2
construction, combination and arrangement of parts as properly fall within the spirit and scope of the invention as claimed.

Having thus described my invention, what I claim and desire to secure by Letters Patent, is:

In a machine of the character described the combination of an electric motor, a primary tubular shaft mounted in said motor, 10 a secondary shaft rotatable with but slidably longitudinally within said primary shaft,

and a switch associated with said motor to control the current thereto and which is automatically closed by longitudinal movement in one direction of said secondary shaft. 15

In testimony whereof I affix my signature in the presence of two witnesses.

HEZEKIAH POWELL.
